UNITED STATES PATENT OFFICE.

ERNST ZINDEL, OF ERLENBACH, SWITZERLAND, ASSIGNOR TO THE FIRM: SCHÄRER-NUSSBAUMER & CO., OF ERLENBACH, SWITZERLAND.

PIRN WINDER.

Application filed March 9, 1927, Serial No. 172,984, and in Switzerland March 30, 1926.

The present invention relates to improvements in pirln winders for producing pirlns having at least one conical end by means of a traversing thread guide.

5 According to the invention the thread guide is operatively connected to a link lever imparting motion to the thread guide, said lever being turnable about a stationary pivot and being actuated by a sliding piece 10 which receives its movement from a rotating cam element but is automatically adjusted on the lever for the purpose of shortening the stroke of the thread guide, the sliding piece being provided with a pin by means 15 of which it is directly connected to said link lever and the slide.

A constructional example of the subject matter of the present invention is illustrated on the accompanying drawings, in which:

20 Fig. 1 is an elevation with parts shown in section of the pirln winder,

Fig. 2 is a plan view,

Fig. 3 is a section along line III—III in Fig. 1 and

25 Fig. 4 is a section along line IV—IV in Fig. 1.

Referring now to the drawings 1 is the casing of the winder having an extension 2 provided with two threaded holes 3 and 4, 30 into the latter of which the pivot pin 6 of the link lever 8 is screwed. 9 denotes a roller connected to the rod 10 of the thread guide and cooperating with the link lever 8. Into the latter projects a pin 11 carrying a 35 roller and fixed to the sliding sleeve 12, the guide rod 13 of which is linked by means of screws 16 and 17 to two levers 18 and 18', mounted in brackets 19 of a stationary bridge member 19'. The spring 20 acting 40 on the lever 18 causes a second arm of the lever 18' to be pressed against a roller 34. The second arm of the lever 18' is provided with a cam face 18'' by means of which it cooperates with the roller 34 during the 45 working of the winder as will be explained hereinafter.

The sliding sleeve 12 is provided with an extension 12', projecting into a longitudinal slot 35 of the bridge member 19' whereby 50 a turning motion of the sleeve 12 is prevented. The pin 11 provided on the sliding sleeve 12 is further in engagement with a transverse slot of a slide 24 arranged below the lever 8, so that these parts are in direct 55 connection with each other which feature

simplifies the construction of the means controlling the thread guide. The slide 24 fixed to a rod 26 is passed through by the rod 10 of the thread guide and by the supporting rod 25 and carries a roller 29 for 60 engagement with the cam groove 30 of the cam body 33. The supporting rod 25 is stationary and the rod 26 is endwise displaceably mounted in sockets 27 of the casing.

65 The roller 34 is arranged on an arm 37, adjustably mounted on a stirrup 38. The latter is turnable about a pivot 39 mounted on a support 40, which in its turn is turnable about an axle 41 disposed at right 70 angles to the pivot pin 39. A spring 42 held by the axle 41 tends to press the stirrup in one direction against a roller 43 and to press thereby the pirln tube 44 which is removably 75 inserted in the stirrup or the pirln S to be formed against the cylinder 43.

On winding the pirln S, the tube of which is assumed to be conical, the stroke of the thread guide 45 fixed to the rod 10 becomes gradually smaller so that the pirln is conical 80 at both ends. This is effected in that the stirrup 38 is turned away from the cylinder 43 as the thickness of the pirln increases, whereby the roller 34 which takes part in the movement of the stirrup 38 causes a 85 corresponding displacement of the elements 18', 13, 18 of the parallel motion device. In the same degree in which this device is adjusted the sliding sleeve 12 on the rod 13 is brought nearer to the bridge member 19' so 90 that the coupling pin 11 provided on the sliding sleeve 12 is displaced along the longitudinal slot of the link lever 8 as well as in the transverse slot of the slide 24 and moves thus away from the pivot pin 6 of 95 the lever 8. In consequence thereof the extent of the angular movement of the lever 8, to which motion is imparted by the cam body 33 via the slide 24 and the pin 11, is gradually reduced and the stroke of the rod 10 of the thread guide which obtains movement from the lever 8 by the intermediary of the block 9 decreases likewise so that the pirln S obtains conical ends.

By suitably choosing the shape of the cam face 18'' of 100 the lever 18' such an angular adjustment of the stirrup 38 and a reduction of the stroke of the thread guide is obtained that the ends of the pirln are formed by cones having a straight generatrix. Obviously the lever 18' 110

may also be provided with a guide slot adapted to receive the roller 34.

A displacement of the pin 6 from the threaded hole 4 into the threaded hole 3 of the bracket 2 causes the gradual reduction of the stroke of the rod of the thread guide in one direction is more pronounced than in the other direction so that the pirn to be wound to a larger cone on one end (at the pointed end) than at the other end. The adjustability of the stationary fulcrum of the lever may also be so made that only one end of the pirn is wound to form a cone whilst the other is straight.

15 The present pirn winder is of a compact design and yet permits to wind pirns of a great length.

Obviously cylindrical pirns may be wound as well as conical pirns in the described manner, i. e. having one or two conical ends.

This is accomplished as follows:

As shown, it is supposed that the pirn tube 44 is conical, thus determining the basic form (conical) of the pirn. The tube 44 and the pirn S as it is wound thereon is pressed by the pivoted spring-urged stirrup 38 against the cylindrical friction roll 43. This stirrup 38 is pivoted at 39 and also on spindle 41, forming two rectangular axes.

30 As shown, the lever 8 is vibrated on its pivot 4 with decreasing amplitude and the pirn will have both ends conical.

By placing pivot 6 in the hole 3, Fig. 2, of the link lever 8 the pivot point is shifted closer to the cam 30, so that lever 8 will cause the formation of a pirn having its butt end or larger end of a shorter taper than the smaller front end.

When the lever 8 does not swing beyond a perpendicular from the thread guide rod 10 passing through the pivot point 4, the pirn is then tapered only at one end, namely the smaller end; now if, instead of using a conical cop tube 44, a cylindrical tube is used mounted in the stirrup 38, the pirn is given cylindrical form, and may be made tapered on both ends, in the position of the parts shown in Figs. 1 and 2.

If the pivot 6 is shifted, as before described, to 3, then this cylindrical pirn will have a greater taper at one end than at the other, while if the lever 8 be given a movement so that the part carrying roller 9 will be vibrated only in one direction from its initial or starting position, the cylindrical pirn will be tapered only at one end, the left hand end Fig. 1.

I claim:

1. A pirn winder for producing pirns having at least one conical end, comprising in combination a traversing thread guide, a link lever turnable about a stationary pivot and operatively connected to said thread guide, a cam body, a slide adapted to be reciprocated by said cam body, a sliding piece to which a

reciprocating motion is imparted by said slide, said sliding piece being directly coupled with said link lever and said slide, and means adapted to automatically displace said sliding piece relatively to said link lever for gradually reducing the stroke of the thread guide.

2. A pirn winder for producing pirns having at least one conical end, comprising in combination, a traversing thread guide, a slotted lever turnable about a stationary pivot and operatively connected to said thread guide, a cam body, a slide provided with a slot and adapted to be reciprocated by said cam body, a sliding piece, a pin on said sliding piece cooperating with said slotted lever and the slot in said slide, whereby an oscillating motion is imparted to said slotted lever and thereby a reciprocating motion to said thread guide, and means adapted to automatically displace said sliding piece relatively to said slotted lever for gradually reducing the stroke of the thread guide.

3. A pirn winder for producing pirns having at least one conical end, comprising in combination, a traversing thread guide, a slotted lever turnable about a stationary pivot and operatively connected to said thread guide, a cam body, a slide provided with a slot and adapted to be reciprocated by said cam body, guide means carried on parallel links, a sliding piece slidably mounted on said guide means, a pin on said sliding piece cooperating with said slotted lever and the slot in said slide whereby an oscillating motion is imparted to said slotted lever and thereby a reciprocating motion to said thread guide, and means adapted to automatically displace said guide means and thereby said sliding piece relatively to said slotted lever for gradually reducing the stroke of the thread guide.

4. A pirn winder for producing pirns having at least one conical end, comprising in combination, a traversing thread guide, a slotted lever turnable about a stationary pivot and operatively connected to said thread guide, a cam body, a slide provided with a slot and adapted to be reciprocated by said cam body, guide means carried on parallel links, a sliding piece slidably mounted on said guide means, a pin on said sliding piece cooperating with said slotted lever and the slot in said slide whereby an oscillating motion is imparted to said slotted lever and thereby a reciprocating motion to said thread guide, and means adapted to automatically displace said guide means and thereby said sliding piece relatively to said slotted lever for gradually reducing the stroke of the thread guide, said means including a cam face in rigid connection with one of said parallel links and an abutment member cooperating with said cam face.

5. A pirn winder comprising in combina-

tion, a traversing thread guide, a link lever turnable about a stationary pivot and operatively connected to said thread guide, a cam body, a slide adjusted to be reciprocated by said cam body, a sliding piece to which a reciprocating motion is imparted by said slide, said sliding piece being directly coupled with said link lever and said slide, means adapted to automatically displace said sliding piece

relatively to said link lever for gradually reducing the stroke of the thread guide, and means to permit the shifting of the pivot point of said lever to change the shape of the pins ends.

In testimony whereof, I have signed my name to this specification.

ERNST ZINDEL.
